SAUCE BOTTLE

Neil W. Miller, Manheim Township, Lancaster County, Pa., assignor to Campbell Soup Company, Camden, N.J., a corporation of New Jersey

Filed June 24, 1965, Ser. No. 85,895

Term of patent 14 years

(Cl. D58—6)

FIG.1.

FIG. 2.

FIG. 4.

FIG.3.

FIG. 1 is an elevational view of a sauce bottle, embodying my new design;

FIG. 2 is a plan view thereof;

FIG. 3 is a bottom view thereof; and

FIG. 4 is a sectional view taken along line 4—4, FIG. 1. I claim:

The ornamental design for a sauce bottle, substantially as shown.
